COSMETICS CABINET

Lois A. Huncovsky, 4897 Hidalgo,
San Diego, Calif. 92117

Filed Nov. 22, 1966, Ser. No. 4,771

Term of patent 14 years

U.S. Cl. D33—19
Int. Cl. D6—01

FIGURE 3 is a side elevation, the side elevations being the same for both sides; and

I claim:

The ornamental design for a cosmetics cabinet, substantially as shown and described.
